United States Patent Office

Des. 214,877
Patented Aug. 12, 1969

214,877

CONTAINER FOR PERFUME OR THE LIKE

Thomas M. Biallo and Olga M. Biallo, both of 430 E. 56th St., New York, N.Y. 10056

Filed May 20, 1968, Ser. No. 12,007

Term of patent 14 years

Int. Cl. D9—01

U.S. Cl. D9—168

We claim:

The ornamental design for a container for perfume or the like, substantially as shown and described.
